UNITED STATES PATENT OFFICE.

CHRISTAN SCHARRINGHAUSEN, OF ELGIN, ILLINOIS.

BACK-PAD FOR HARNESS.

SPECIFICATION forming part of Letters Patent No. 242,376, dated May 31, 1881.

Application filed February 19, 1881. (No model.)

To all whom it may concern:

Be it known that I, CHRISTAN SCHARRINGHAUSEN, a citizen of the United States, resident at Elgin, in the county of Kane and State of Illinois, have invented certain new and useful Improvements in Back-Pads for Harness; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, and in which—

Figure 1 is a representation of a sectional view, and Fig. 2 is a perspective view, of the same.

This invention relates to saddle-trees, more particularly the pad-iron therefor.

The invention consists in the construction hereinafter described, and particularly pointed out in the claim.

In the drawings hereto annexed, A is the pad-iron for a saddle-tree, having the curved form, as shown. The edges B B are turned upward, forming the flanges b b, as shown.

E F F are three bosses rising from the upper face of the iron, and screw-threaded internally at e f f, to receive the threaded shanks of the water-hook and terrets. The saddle-leather comes over the face of this iron, fitting snugly between the flanges b b, the bosses passing up through perforations in the leather, their heights being sufficient to receive two thicknesses of leather, which is usual in making pads. 30 n are holes near the bosses f f, for additionally securing the leather to the pad. 35

What I claim is—

An improved article of manufacture, a pad-iron for saddle-trees, provided with the up-turned edges b b, the central threaded boss, E e, and the threaded side bosses, F f, all rising from the upper face of the pad-iron, as and for the purposes set forth. 40

In testimony whereof I affix my signature in presence of two witnesses. 45

CHRISTAN SCHARRINGHAUSEN.
